UNITED STATES PATENT OFFICE

LESLIE A. RUSSELL, OF MILWAUKEE, WISCONSIN, ASSIGNOR TO KOEHRING COMPANY,
OF MILWAUKEE, WISCONSIN, A CORPORATION

INSTROKE SHOVEL CRANE

Application filed March 26, 1928. Serial No. 284,601.

By my present invention, I propose certain novel improvements in excavating machinery of the crane shovel type, known in the art as in-stroke or hoe type shovels of the portable power operated class. These shovels are found especially advantageous in the digging of trenches because they afford a very considerable flexibility of operation and ample power to perform their excavating function; moreover, they readily accommodate for the excavation of trenches on the curved operations or where one branch of a trench may extend off from another at a more or less sharp angle.

The new features of my invention reside primarily in the mounting of the shovel boom upon the crane body, known as the swing body, and the peculiar arrangement and action of the shovel dipper in its relation to the boom, together with novel provisions affording a yielding mounting for the shovel or dipper itself. The yielding means cooperating with the dipper proper really performs a three-fold function in that it absorbs shocks in the pull cable when digging; absorbs shocks upon the whole supporting structure including the dipper boom and connections when the dipper is operated as a sort of pick or hammer. Additionally, the yielding means absorbs shocks at the end of the boom where the dipper is mounted with the dipper stick, when the dipper is slammed out to its extreme position for dumping; at the same time the absorbing means permitting a shifting of the angle of the dipper relatively to the stick to assist in the disengaging of clogging or sticking materials in the dipper.

With the foregoing and other objects in view, the advantages of my invention as presented herein in different forms, will be quite apparent upon reference to the drawings appended hereto, and I might note furthermore, that I employ a dipper structure in which the pull cable means may consist of provisions in the form of a cable sling around the dipper, should this type of pull cable instrumentality be desired; or a pull cable attaching to a chain pull connection secured to the dipper may be utilized.

In the accompanying drawings:—

Figure 1 is a side view of an in-stroke shovel crane embodying the invention and showing the angle at which the boom may be adjusted downwardly as when undercutting a bank or trench, dotted lines indicating the 56 dipper in its up-pulled filled position.

Figure 2 is an enlarged view of the means shown in Figure 1, involving the outer end of the boom and the dipper mounting features.

Figure 3 is a front and partly sectional view taken about on the line 3—3 of Figure 2 looking in the direction of the arrows.

Figure 4 is a front view of the dipper stick of the construction of shovel means illustrated in the previous figures, the mounting connections of the dipper being broken away and the cable pull connection for the dipper stick being shown in section.

Figure 5 is a view partly in section and partly in top plan, illustrating the cable operating means for pulling in the dipper.

Figure 6 is a view somewhat similar to Figure 2 but depicting a modified form of the invention.

Figure 7 is a front view, partly broken away showing more clearly the cable out-pull means for the dipper stick, and the manner of its connection with the stick as it leads from the upper side of the boom.

Figure 8 is a side view showing a portion of the supporting boom and a modified type of dipper and dipper supporting means including a dipper stick which is pivoted between its ends.

Figure 9 illustrates a modified form of pulling in cable means for the dipper, including a sling that passes around the dipper and is self equalizing.

Figure 10 is a view in side elevation largely showing the parts depicted in Figure 9.

Figure 11 is a diagrammatic illustration of the reeving of the cable means and associated parts.

In the drawings, A denotes the portable base of my shovel crane upon which is located the usual rotative or swing body B, see Figure 1. Carried at one end of the body B is a main supporting boom 1 formed with the outstanding arm 2, rigid therewith, and braced 100

by a brace 3, the structure as a unit being therefore of somewhat triangular formation. Upon the outer end of the arm 2, there is pivoted at 4, the dipper boom 5 equipped at its inner end with a foot member 6 provided with the cable guiding sheaves 7 and 8. The foot member 6 may be united with the body of the boom 5 by a yielding connection of the type disclosed in my copending application 10 for patent, Serial No. 723,623, filed July 2nd, 1924, so that certain torsional stresses upon the body of the boom 5 may be resiliently absorbed at the foot, these stresses being produced by the swinging of the boom ordinarily, and its stoppage with the loaded dipper, with greater or less suddenness, or the stresses may be set up by the dipper or dipper stick striking an obstacle in its path during the lateral swing of the boom.

20 Upon the under-side of the boom 5 and spaced from the outer end thereof, is a bracket 9 to which is pivoted the dipper stick 10, the latter as seen in Figure 4 being a fabricated rigidly constructed unit composed of side 25 members, the outermost ends of which are pivotally connected at 11 to the upper open end portion of the dipper 12, see Figure 2. The rear upper or closed end of the dipper 12 is pivotally and adjustably connected as 30 shown at 13 by a link member or members 14 which in turn have attachment to a piston or plunger 15 by pivotal means 16. A series of openings 17 provide for the adjustable connection at 13, and the plunger 15 operates in a 35 cylinder 18 rigid with the dipper stick body structure and containing a normally expanding spring 19. The plunger 15 is loosely connected by a bolt or similar fastening 20 passing through the closed end of the cylinder 18 and attached to a rocker arm or bell crank 40 lever 21 pivoted at 22 to the dipper stick 10. The arm of the lever 21 opposite that connected with the bolt 20 is arranged to engage an abutment bracket 23 rigidly attached to 45 the underside of the boom 5 at its outer end portion.

It is apparent that the bell crank lever 21 constitutes an abutment carried by the dipper stick 10 and which abutment cooperates 50 with the boom 5 in limiting the relative movement of these parts.

Connected with the front end of the dipper 12 at a point 24 in advance of the point of connection 11 between the dipper and its 55 stick 10, is a pulling in chain or equivalent connection 25 attached to the pulling in cable 26 which leads therefrom, to and around a small drum 27 mounted upon the boom 5 upon an axis 28 which also carries a larger 60 operating drum 29 about which is wrapped and secured, the operating end portion of the pulling in operating cable 30. I call the cable 30 an operating cable simply to distinguish it from the pull cable 26, and the terms are 65 merely relative terms and could be inter-

changed so far as the description goes, but are distinguishable for clearness. Since the drum 27 is a small drum and the drum 29 comparatively larger, it will be recognized that the latter affords a leverage for operating the drum 27 with great crowding in force, which is ample to accomplish the desired excavating or digging action of the dipper 12.

As customary in shovel cranes of the in-stroke type, there is provided an out-pull cable for causing the out-stroke and dumping movement of the dipper and for elevating the boom 5 in the operation of emptying the dipper to supply its contents to a spoil bank, or to a vehicle in which the material will be carried away. In the present instance, I utilize the out-pull cable means 31 leading from a suitable drum upon the crane swing body B over a large double sheave 32 at the upper end of the supporting boom 1 thence extending downward at the bight 32' through the sheave block 34, thence extending upward by the bight 32'' around the second grooved portion of the pulley or sheave 32, and thence extending downward by the bight 32''' and over a sheave 35 on the point bracket 36 of the boom 5 to its point of attachment by a suitable clamp 37 to the cylinder 18 on the dipper stick structure 10. Obviously, operation of the cable 31 will transmit to the dipper stick and its associated parts, a powerful out-haul pull, and slack on the line or cable 31 will permit lowering of the boom 5 and adequate crowding in action in the operation of the pulling-in cable 26.

I make provisions for varying the upward or downward adjustment of the pivot point 4 of the boom 5, and therefore, the point of support of the boom 5 upon the main supporting boom 1, by raising and lowering the boom 1 to a greater or less extent correspondingly adjusting its arm 2. To do this I employ a drum 38, seen in Figure 1, rather diagrammatically, about which drum the boom hoist cable 39 passes and leads off so as to pass around a small sheave 40 at the upper end or point of the main supporting boom 1, the cabling thence leading back to a pulley 41 and passing around another sheave 40, said sheaves being spaced apart, and then being led to a point of anchorage 42. The purpose of the method of reeving the cable 39 is simply to afford ample power for the operation of the boom 1 and the heavy load 115 which it carries, and may be considerably modified within the purview of the invention obviously.

I described the operation of the machine thus far set forth herein, as follows: assuming that the dipper 12 is in the full line position of Figure 1, and that the operating cable 30 leads to a suitable front drum 43 on the swing body, it will be apparent that operation of the drum 43 will produce an 125

in-haul movement of the out pull cable 26 and chain 25 and effect the digging action of the dipper 12 as the boom 5 is likewise swung inward if the out-haul and hoisting cable 39 is slackened. Of course, the drum about which the cable 31 operates and the drum 43 will have suitable braking means to control them as well as clutch means to establish the drive between the engine and said drums.

5 The dipper being locked with the excavated material, the cable 30 is slackened and the drive for pulling in the cable 31 established and the operation of the cable 31 will then raise the dipper and the boom 5 to move it toward its dumping position, a final slackening on the cable 30 permitting the cable 31 to swing the dipper stick 10 with the dipper 12 upwardly and outwardly relatively to the boom 5 to perform the function which to those versed in the art is called "spotting the load" in depositing the contents of the dipper 12 in a vehicle, or upon a spoil bank.

Now during the above operation of the dipper by the cables 30 and 31 in the manner set forth, peculiar action of the dipper itself takes place. The spring 19 in the cylinder 18 is normally full expanded with the rear end of the dipper as far away from the stick 10 as possible. But as the dipper stick 10 swings on the boom 5 in the dumping operation of the dipper, the lever 21 engages the abutment 23 and the lever is swung to place the spring 19 under tension and pull 35 on the link 14 and swing the dipper 12 slightly on its pivot 11. Under these conditions, the shock absorbing means just referred to absorbs the shock of the sudden stopping of the dipper in what may be called its up-slam 40 movement to dump. Additionally, the absorbing means affords a desirable resilient shocking action that tilts the dipper on its stick and facilitates the dislodgement of materials filled therein. Of course, as the dipper is thus swung, its door 44 which is pivoted at 45 in rear of the point of connection 45 of the chain 25 and the pivot point 11 connection with the dipper, may be opened by the operation of the dipper door trip latch 50 by its chain 45 and cable means 46 leading from the chain 1 a suitable point near or on the swing body B of the crane.

In trench or hoe type shovels of the class 55 of the invention, the excavating operation is often facilitated by dropping the boom and shovel 12 upon the work or earth excavated to provide a picking action. Also in this way, the dipper is sometimes used as a hammer in 60 excavating rocky deposits to break up the deposits. Obviously, under these conditions, the dropping of the dipper, while it is in approximately the relation shown in Figures 1 and 2 to the boom 5 will cause an absorption 65 of the shock incident to the engagement of

the teeth of the dipper with the work, by the yielding means, including the spring 19.

I will now describe a couple modified forms of the invention, after stating that the cable 31 is connected to the dipper stick at a point 70 between its ends and has a variable leverage

in its pull upon the dipper stick for obvious reasons. In Figures 6 and 7, I show a construction which is somewhat unique in that the dipper stick 10^a is mounted on the boom

75 5^a at the point of the boom itself, practically speaking, the pivotal axis 47 for the dipper connection to the boom providing an axis for spaced sheaves 48 about which passes the sides of the out-haul cable loop 49, as best seen in Figure 7. The cable loop 49 passes around

80 and thus connects with the stick 10^a as shown at 50 in Figure 6 and since the distance between the cable loop 49 and the axis 47 of the stick 10^a is constant during all of the range

85 of movement of the stick relatively to the boom 5^a a constant leverage pull by the cable 49 upon the stick is exercised in the operation

89 of the out-haul cable means which includes in addition to the loop 49, the main out-haul cable 31^a having a function equivalent to the cable 31 described in the first form of the invention set forth. The cable loop 49 is attached to the floating pulley or sheave block

95 51 in an obvious manner as seen from Figure 7, the points of attachment being designated 52. In Figure 6, I provide shock absorbing

100 facilities for the dipper corresponding with those previously set forth, the only difference being practically speaking, that the shock absorbing means is slightly differently arranged upon the stick 10^a as to angularity

105 and a somewhat reverse arrangement of the lever 21^a to that of the previously described lever 21, is used. The lever 21^a, however, co-

110 operates with an abutment part on the boom 5^a, designated 23^a, in much the same manner as previously disclosed herein for the first

115 described form of an invention. Parts not otherwise designated or described as to Figures 6 and 7, are substantially like those first

120 disclosed herein.

In Figure 8, the dipper boom is designated 5^b. It carries the dipper stick 10^b pivoted between its ends at 52—53 to the boom 5^b at the

125 point of the latter. Boom 5^b has the abutment 23^b cooperative with an angle lever 21^b which is connected up with the shock absorbing

130 spring means 19^b acting in practically the same way as described in reference to the other constructions of my invention. In

Figure 8, the out-haul cable or line 31^b has a somewhat different leverage effect by reason of connecting with the lever forming the

135 dipper stick 10^b at the point 54 some distance above the point of connection with the stick of the boom 5^b. But this leverage action is old and well known to those versed in the art

140 of this type of machine. The construction proposed illustrates that my shock absorbing

features may be availed of for the intermediate pivoted type of dipper stick as well as one pivoted at its end to the end of the boom or pivoted at an end to the boom at a point some distance away from the end of the latter.

In Figure 9, I illustrate a different construction of pulling in cable means for the dipper 12. Said pulling in cable means includes a cable sling 55 which passes around the dipper and by slippage relatively to the guiding means 56 on the dipper will be self equalizing. The cable means 55 has its sides wrapped about spaced small drums 57 in one direction, upwardly as illustrated and secured at the ends to these small drums. Intermediate of the drums 57 is a larger drum 58, and a main pulling-in operating cable 59 is wrapped about it and secured thereto, the direction of wrapping or reeving being opposite that to the direction in which the cable means 55 passes around the drums 57. Of course, the drum means 57 and 58 will be carried by a boom or like support 56 and will constitute the in-haul cable means for crowding in the bucket to its work. Under certain conditions of service, a sling like crowding cable means such as first described, may be found advantageous. The drums 57 and 58 are, of course, coaxial.

It will be noted that the drums 27 and 29 may be equipped with removable or interchangeable drum laggings or cable reeving portions whereby to enable an increased or decreased speed of the particular cable wrapped therearound, in the actuating operation of said drums.

Having thus described my invention, what I claim as new and desire to secure by Letters Patent of the United States, is:—

1. In combination, a hoe type shovel crane comprising a swing body, a main supporting boom thereon having an off-standing dipper boom arm, means for raising and lowering the said dipper boom arm of the main supporting boom, a dipper boom pivoted to the dipper boom arm, and an in-stroke dipper mounted upon the dipper boom, with means for controlling the crowding in and the out-haul movements of said dipper.

2. In a shovel crane of the type set forth, in combination, a crane body, a main supporting boom thereon, comprising an outstanding arm pivotally carried by the body for up and down movement, means for raising and lowering the said arm, a dipper boom pivoted to the outer portion of said arm, an in-stroke dipper carried by the outer portion of the dipper boom, and crowding in and out-haul cable means cooperating with the said dipper and the dipper boom for controlling their proper action.

3. In a shovel crane of the type set forth, in combination, a crane body, a main supporting boom thereon, comprising an outstanding

arm pivotally carried by the body, means for raising and lowering the said arm, a dipper boom pivoted to the outer portion of said arm, an in-stroke dipper carried by the outer portion of the dipper boom, and crowding in and out-haul cable means cooperating with the said dipper and the dipper boom for controlling their proper action, and crowding in cable drum mechanism mounted on the dipper boom as a part of the last mentioned means and including a drum of small diameter connected with the dipper for crowding in action on the latter and a drum of larger diameter for actuating the last mentioned drum.

4. In an excavating machine as set forth, in combination, a crane body, a dipper boom mounted thereon, a dipper stick pivoted to the dipper boom, a dipper carried by the dipper stick, and shock absorbing means intermediate said dipper and the dipper stick for absorbing shocks incident to picking or hammering action of the dipper when dropped, and also for absorbing shocks incident to out-slam movement of the dipper for dumping, with means cooperating with the shock absorbing means for limiting the extent of its movement in effecting spotting or dumping action.

5. In a machine of the class set forth, in combination, a dipper boom, a dipper stick mounted thereon, means for moving the stick relatively to the boom in excavating and other operations, a dipper on said stick, and shock absorbing means intermediate the boom and the stick, and including an abutment on the stick adapted for cooperation with the boom and limiting the relative movement of the stick and the boom.

6. In a machine of the class set forth, in combination, a dipper boom, a dipper stick mounted thereon, means for moving the stick relatively to the boom in excavating and other operations, a dipper on said stick, and shock absorbing means intermediate the boom and the stick, and including an abutment on the stick adapted for cooperation with the boom and limiting the relative movement of the stick and the boom, and a spring connection intermediate the dipper and its stick, and co-acting with the abutment aforesaid.

7. In a machine of the class described, in combination, a dipper boom, a dipper stick pivoted thereto, a dipper pivoted to the dipper stick, and a yielding connection between the dipper and the dipper stick separate from the pivotal connection of the dipper with the stick, and including a link arm attached to the dipper and spring means intermediate the link arm and the dipper stick, and means carried by the boom for acting upon said spring connection to absorb certain shocks.

8. In a machine of the class described, in combination, a dipper boom, a dipper stick pivoted thereto, a dipper pivoted to the dip-

per stick, and a yielding connection between the dipper and the dipper stick separate from the pivotal connection of the dipper with the stick, and including a link arm attached to the dipper and spring means intermediate the link arm and the dipper stick, an abutment means on the boom for acting on said spring connection to cause rocking of the dipper in its dumping action together with crowding 10 and hauling cables for working the dipper stick in opposite directions.

9. In a machine of the class described, in combination, a dipper boom, a dipper stick pivoted to said boom, a dipper pivoted near 15 one end to the dipper stick, a linkage connection between the dipper stick and the other end of the dipper, and means on the boom cooperative with said linkage connection for rocking the dipper at a certain point in the 20 relative movement of the dipper and boom.

10. In a machine of the class described, in combination, a dipper boom, a dipper stick pivoted to said boom, a dipper pivoted near one end to the dipper stick, a linkage connection 25 between the dipper stick and the other end of the dipper, and means on the boom cooperative with said linkage connection for rocking the dipper at a certain point in the relative movement of the dipper and boom, 30 said linkage connection including a yielding element for absorbing shocks between the dipper and dipper stick.

11. In a machine of the class described, in combination, a dipper boom, a dipper stick pivoted to said boom, a dipper pivoted near 35 one end to the dipper stick, a linkage connection between the dipper stick and the other end of the dipper, and means on the boom cooperative with said linkage connection for 40 rocking the dipper at a certain point in the relative movement of the dipper and boom, said linkage connection including a yielding element for absorbing shocks between the dipper and dipper stick, and cooperating with 45 the boom for absorbing shocks intermediate the dipper stick and the boom.

12. In a machine of the class described, in combination, a dipper boom, a dipper stick pivoted to the said boom at one end, a dipper 50 carried by the other end of said stick and movable relatively thereto, and shock absorbing means between the dipper and the dipper stick including a linkage connection of said parts and a spring acting upon said linkage 55 connection, an abutment upon the boom, and a lever cooperating with said linkage connection by inter-action with the abutment on the boom.

13. In a machine of the class described, in combination, a dipper boom, a dipper stick carried by the boom, a dipper carried by the dipper stick, said dipper boom and dipper stick being relatively movable with respect 60 to one another, an abutment for limiting the 65 said relative movement, and connections be-

tween the dipper and dipper stick operable incident to the dipper boom and dipper stick reaching their limit of movement causing engaging of the abutting means, to move the dipper relative to the dipper stick, whereby 70 the dumping of the contents of the dipper is facilitated.

In testimony whereof I affix my signature.
LESLIE A. RUSSELL.
